CIRCUIT BREAKER

Marion H. Rowe, Dallas, Tex., assignor, by direct and mesne assignments, of seventy-two and one-half per cent to Joseph H. Reynolds, Cisco, Tex., and five per cent to Jack A. Schley, Dallas, Tex.

Application April 1, 1937; Serial No. 134,217

14 Claims. (Cl. 200—124)

This invention relates to new and useful improvements in circuit breakers.

One object of the invention is to provide an improved electrical circuit breaker which is particularly adapted for use in the usual fuse box being substituted for the usual plug-type fuse.

An important object of the invention is to provide an improved electrical device adapted to be inserted into the usual electrical receptacle and which acts as a circuit breaker to break the electrical circuit upon a short circuit or overload, and which is arranged to be reset to circuit closing position by merely removing the device partially from the receptacle, whereby the electrical current is not flowing through the device during the resetting thereof, which eliminates spark, as well as danger of electrical shock to the operator during the resetting operation.

Another object of the invention is to provide an improved circuit breaker of the character described having a latch member held in circuit closing position by fusible material so that upon overload or short circuit said material is melted or liquefied to permit the latch to be disengaged to open the circuit; with means for automatically restoring the latch to its normal position while the fusible material is solidifying through cooling, whereby the latch may be reset to circuit closing position and the device repeatedly used.

Still another object of the invention is to provide an improved circuit breaker of the character described wherein the setting of the device to circuit closing position is directly controlled by the insertion of the device into an electrical receptacle, or other operating position.

Still another object of the invention is to provide an improved device of the character described, wherein a movable yoke member is arranged to close the electrical circuit through the device with an improved latch for holding the same in circuit closing position, said latch being so constructed as to produce a snap action, thereby minimizing danger of spark and prolonging the life of the device.

A construction designed to carry out the invention will be hereinafter described, together with other features of the invention.

The invention will be more readily understood from a reading of the following specification and by reference to the accompanying drawings, in which an example of the invention is shown, and wherein:

Figure 1 is an elevation of a circuit breaker, constructed in accordance with the invention,

Figure 2 is an elevation of a circuit breaker,

mounted within an ordinary electrical receptacle, the latter being shown in section,

Figure 3 is a transverse vertical sectional view of the part shown in Figure 2 and showing the latch in circuit closing position.

Figure 4 is a view similar to Figure 3 with the latch in its disengaged position,

Figure 5 is a view similar to Figure 3, and taken at right angles to said figure, with the device in circuit closing position,

Figure 6 is a view similar to Figure 5 with the electrical circuit broken,

Figure 7 is a transverse vertical sectional view of a circuit breaker as shown in Figure 1 and with the part in circuit closing position,

Figure 8 is a plan view of the circuit breaker in circuit closing position,

Figure 9 is a similar view showing the designation visible in the top of the circuit breaker when the circuit therethrough is broken,

Figure 10 is a bottom view of the circuit breaker,

Figure 11 is a horizontal cross-sectional view, taken on the line 11—11 of Figure 3,

Figure 12 is a horizontal, cross-sectional view, taken on the line 12—12 of Figure 3,

Figure 13 is a horizontal, cross-sectional view, taken on the line 13—13 of Figure 7,

Figure 14 is an isometric view of the connecting yoke and latch, and

Figure 15 is a detail view showing the movement of the latch member when the fusible material is heated.

In the drawings, the numeral 10 designates a hollow cylindrical shell or housing which is constructed of glass, or other electrical non-conducting material.

One end of the housing is open while the opposite end is closed by an end wall 11, which wall is provided with an internal axial recess 12. The upper end of the end wall may also be recessed as shown at 11'. The end wall is preferably made integral with the housing or shell and an annular outwardly extending flange 13 is formed at this closed end of the shell. The shell or housing is substantially of the same diameter as the ordinary plug-type fuse, whereby it may be inserted in the usual electrical receptacle 14 which receives such fuse. An insulating block 15 constructed of a suitable electrical non-conducting material, such as "Bakelite", is arranged to be inserted into the open end of the shell or housing 10.

The block is provided with an external shoulder 16 which engages the end of the housing and as clearly shown in Figures 3 to 7 the upper end of the block is received within the housing or shell. When said block is

5

55

inserted within the shell, an annular metallic collar 17 is threaded on the exterior surface of the block and also on the exterior surface of the lower end of the shell. The collar 17 is provided with an inturned annular flange 18 which engages an external shoulder 19 formed on the block 15. With such arrangement the metallic collar 17 serves to connect the shell 10 with the block 15. The lower end of the block below the collar 17 is tapered or reduced toward its center. It will be manifest that the block and shell when connected by the collar 17 provide a device which is substantially of the same size and shape as the ordinary plug-type fuse.

15. The threads of the collar 17 are formed by a pressing operation, whereby said collar is provided with external as well as internal threads. These external threads may be utilized for screwing the device into the usual electrical receptacle 14 which is provided for the reception of plug-type fuses. It is noted that the collar 17 may be riveted or otherwise secured to the shell 10 and block 15 and the invention is not to be limited to threading said collar thereon although 25 this latter method makes for easy disassembling of the device.

For conducting electrical current through the circuit breaker, the lower reduced end of the block 15 is provided with a circular contact 20, 30 and this contact has an upwardly extending contact bar 21 integral therewith (Figures 5 and 6). The contact bar 21 extends upwardly through the block 15, being preferably molded therein and the upper end of this bar terminates at a 35 point substantially in horizontal alignment with the external shoulder 16 of the block. The extreme upper end of the bar 21 extends into an opening 22 which is provided in the block and which is substantially rectangular in cross-section (Figure 12). The opening 22 extends from the top of the block 15 to a point below the upper end of the contact bar 21. Manifestly, when the device is inserted into the usual electrical receptacle 14, the circular contact 20 at the lower 40 end of the block 15 will engage the usual axial contact A of the receptacle whereby the electrical current may flow upwardly through the bar 21 which is integral with the contact 20.

50. Diametrically opposite the rectangular opening 22 is a similar opening 23 which extends vertically of the block 15 (Figures 5 and 6). A short contact bar 24 has its upper end extending into the lower end of the opening 23. The lower end of the bar 24 is bent outwardly so as to extend radially to the outer surface of the block 15. The bar 24 is then bent upwardly so as to extend contiguous to the inner surface of the metallic collar 17. The bar 24 is of course preferably molded within the block 15 and is further held 55 in place by the collar 17. It will be obvious that with the device inserted within the usual receptacle 14, the current will flow from the metallic insert collar B of said receptacle through the collar 17 and then through the arm 24. The other 60 side of the electrical circuit to the receptacle is of course connected to the bar 21 through the contact 20 at the bottom of the block. Therefore, by connecting the bar 21 with the bar 24, the electrical circuit through the device may be 65 completed.

70. For connecting the bars to complete the circuit through the device, a yoke 25 is provided. This yoke is clearly shown in Figure 14 and includes vertical yoke arms 26 connected by a semi-circular connecting member 27, whereby the arms

move together. A laterally directed arm 28 extends from the center of the connecting member 27 and has its extreme outer end offset to provide an indicator 29. This offset portion of the arm 28 has the word "Off" printed thereon. The 5 yoke arms 26 are adapted to be inserted in the rectangular openings 22 and 23 in the block 15 and when moved to a lowermost position, have their lower ends overlapping and engaging the upper end of the bars 21 and 24, whereby an 10 electrical connection is obtained between said bars.

For guiding the yoke 25 in its vertical movement as the yoke arms 26 engage or disengage the bars 21 and 24, a plunger or stem 30 is slidably mounted in an axial bore 31 provided in the block 15. The contact 20 mounted on the reduced lower end of the block is provided with a central opening 20' to permit the plunger 30 to extend therethrough. The upper end or portion 20 of the plunger 30 extends through a slot 29' provided in the arm 28 of the yoke 25. It is noted that the slot 29' of said arm is in axial alignment with the bore 31 of the block. The extreme upper end of the plunger 30 is formed with an integral 25 collar 32 and this collar limits the upward movement of the yoke 25 on the plunger. The bore 31 of the block 15 is enlarged at its upper end as shown at 31', whereby an internal annular shoulder 33 is formed within the bore of the block. A 30 coiled spring 34 is confined between this shoulder and the underside of the arm 28 which is secured to the yoke 25, and this spring exerts its pressure to constantly urge the yoke 25 upwardly with 35 relation to the plunger 30.

For holding the yoke 25 in its lowermost position within the openings 22 and 23, whereby its arms 26 contact the bars 21 and 24 and thereby maintain the device in circuit closing position, an angular latch member 35 is mounted on said yoke. 40 The latch member includes a laterally directed arm 36 and a vertically extending arm 37, as is clearly shown in Figure 14. The laterally directed arm of the latch member overlies the connecting member 27 and the arm 28 of the yoke and has 45 its outer end provided with a slot 36' which slot is in alignment with and of the same size as the slot 29' in the arm 28. The plunger 30 of course extends through the slot 36' of the arm 36. The latch member is secured to the connecting member 50 27 of the yoke 25 by a tongue or lug 38 which is formed on the member 27. This tongue or lug projects through a slot 39 formed in the arm 36 of the latch member and it is noted that the slot is larger than the cross-sectional area of the lug, 55 whereby the latch member may undergo a limited swinging movement with relation to the yoke.

To normally prevent the swinging movement of the latch member 35 with relation to the yoke 25 a fusible material 40 covers the lug 38 and the 60 opening 39 through which said lug extends. When this material is cool, it is a solid and acts as a bond to secure the latch member 35 to the yoke 25. However when this fusible material becomes heated, it melts or softens and an upward 65 pressure against the outer end of the arm 36 of the latch member 35 will cause a swinging movement of the vertical arm 37 of said latch member.

The vertical arm 37 extends downwardly into an opening 41 which is formed in the marginal 70 portion of the block 15. This opening is substantially rectangular in cross-section and has an inwardly projecting shoulder 42 formed at its lower end. The extreme lower end of the arm 37 of the latch member 35 is offset to form a projection 43, 75

which projection is arranged to engage beneath the shoulder 42 to hold the yoke 25 in its lowered position under tension of the coiled spring 34. So long as the device is within the usual receptacle 14, it will be obvious that the plunger or stem 30 engaging the bottom of the receptacle will be forced upwardly into the upper end of the casing or shell 10 or into the position shown in Figures 3 to 6. However, when the device is removed from the receptacle 14 the plunger 30 is forced outwardly from the axial bore 31 of the block 15. This outward movement of the plunger or stem is produced by the action of a coiled spring 44 which is confined between the collar 32 on the stem and the inner end of the wall 11 of the shell. This coiled spring has its upper end located within the recess 12 in said end wall and is stronger than the spring 34 located within the bore of the block, whereby it may overcome the pressure of the latter spring. Obviously, when the device is within a receptacle, the engagement of the plunger 30 with the lower end of the receptacle will move the plunger upwardly under tension of the spring 44. In operation, it will be assumed that the device is in circuit closing position and said device is removed from the usual receptacle 14, in which instance, the part would be in the position shown in Figure 7 with the latch member 35 having the lug at the lower end of its vertical arm 37 engaged beneath the shoulder 42 of the opening 41. The fusible material 40 is of course solidified since the yoke and latch member are cool, whereby the latch member 35 is held in a fixed position on the yoke 25. With the lug 43 at the lower end of the arm 37 of said latch member engaged with the shoulder 42, the yoke 25 is held in its lowermost position as shown in Figures 3, 5 and 7. In this position the arms 26 of the yoke are within the openings 22 and 23 of the block 15 and have their lower ends engaging the upper ends of the contact bars 21 and 24 whereby the electrical circuit through the device is complete. The coiled spring 34 which surrounds the plunger 30 within the bore 31 of the block 15 is of course under compression being held so by the engagement of the latching member with the shoulder 42. At this time the plunger is in its lowermost or extended position with the collar 32 of said plunger engaging the lateral arm 36 of the latch member 35. The plunger is held in this position by the coiled spring 44 which, as has been stated, has a greater pressure than the spring 34.

When the block 15 and shell 10 are inserted into the usual receptacle 14 it will be evident that the outer end of the plunger 30 will engage the bottom of the receptacle and as the metallic collar 17 on the block and shell is threaded into said receptacle, the plunger 30 is moved inwardly within the shell and bore 31 under tension of the spring 44. The plunger is of course made of a suitable electrical non-conducting material and by the time that the device is entirely within the socket or receptacle, the plunger has moved to its innermost or retracted position. This position is clearly shown in Figures 3 and 5 and the collar 32 on said plunger or stem has moved away from the latching member 35 and yoke 25. So long as the device remains in the receptacle the plunger 30 remains in the same position with the spring 44 under tension.

Since the latch member 35 is constructed of a metallic electrical conducting material and

also since it is in engagement with the metallic connecting yoke 25, it will be obvious that the current flowing from the bar 21 through the yoke 25, and to the opposite contact bar 24, will also flow through the latch member 35. Therefore, if a short circuit or overload occurs in the electrical circuit, the fusible material 40 will become heated which will result in a melting or softening of this material. As soon as this occurs, the pressure of the spring 34 which is constantly urging the arm 28 of the yoke 25 and the laterally directed arm 36 of the latch member 35 upwardly, will result in an upward swinging of the outer end of these arms. Since the latch member 35 may undergo a limited swinging movement on the yoke 25 when the fusible material is not solidified, it will be obvious that said latch member will be swung to the position shown in dotted lines in Figure 15. This swinging of the latch member will disengage the lug 43 from the shoulder 42 and will permit the spring 34 to move the yoke and latch upwardly to the position shown in Figures 4 and 6. The upward movement of the yoke and latch carried thereby is of course limited by the collar 32 on the upper end of the plunger 30. When the yoke moves to its upper position the lower ends of its arms 26 are disengaged from the contact bars 21 and 24, whereby the electrical circuit through the device is broken.

The breaking of the electrical circuit permits the fusible material 40 to immediately solidify or harden, whereby the latch member 35 is again securely fastened to the yoke 25. It is noted that since the lateral arm 36 of the latch member 35 strikes the collar 32 upon upward movement of the yoke, and also due to the fact that the spring 34 is urging the part upwardly, the normal position of the yoke is restored before the fusible material 40 hardens. Therefore it is assured that the latch member 35 is always fastened to the yoke 25 by the fusible material in the same position. When the yoke 25 is moved upwardly to the position shown in Figures 4 and 6, the offset indicator 29 which is formed on the outer end of the arm 28 of the said yoke lies beneath the inner surface of the end wall 11, whereby the indicia on said indicator is visible through said end wall, as clearly shown in Figure 9. This indicates to the operator that a short circuit or overload has occurred and that the electrical circuit through the device is broken.

In order to reset the latch member 35 so as to restore the yoke 25 to its circuit closing position, it is only necessary to unscrew the shell and block from the receptacle 14. As this is done the strong spring 44 acting against the upper end of the collar 32 of the plunger 30 will force the plunger outwardly from the bore 31 of the block. The spring 44 is of course acting against the coiled spring 34 but since it is of a stronger pressure, it will easily overcome this spring. As the plunger 30 moves outwardly of the block 15 it will be evident that the latch member 35 and yoke 25 will be moved downwardly toward the block. As soon as the shell 10 is unscrewed sufficiently from the receptacle to permit a complete projection of the plunger 30 from the block 15, the yoke 25 has moved to its lowermost position (Figure 7). By this time the vertical arm 37 of the latch member 35 has moved downwardly in the opening 41, whereby the lug 43 at the lower end of said arm has been re-engaged with the shoulder 42. It is pointed out that it is not necessary to completely unscrew the

shell 10 from the receptacle 14 but only a partial removal of this shell from the receptacle will permit the plunger to complete its resetting operation. Of course, the amount of movement of the shell and block 15 with relation to the receptacle 14 is dependent upon the space between the collar 32 and the upper end of the block 15.

After the yoke and latch member have been reset as explained it is only necessary to return the shell 10 and block 15 into the receptacle whereby the plunger 30 is again returned to the position shown in Figure 5 and the device is again ready for operation. If a short circuit 10 is present in the electrical circuit, the fusible material 40 will again be heated immediately which will again release the yoke, moving the same to its uppermost position, whereby the operator is advised that a short circuit is present. 15 If the disengagement of the latch member 35 was due to an overload, the resetting of the device again closing the circuit will remedy the trouble. With the construction set forth above, it will be evident that the resetting is automatically accomplished by the plunger 30 and 20 the actuation of the plunger is controlled entirely by the position of the device within the receptacle or socket in which it is inserted.

What I claim and desire to secure by Letters 25 Patent is:

1. A circuit breaker arranged to be inserted in an electrical receptacle including, an insulating block, electrical contacts mounted on said block, means for electrically connecting said contacts to close an electrical circuit through said circuit breaker, means for effecting a disengagement of said connecting means from the contacts when an overload or short circuit occurs in the electrical circuit, and means coacting with the receptacle and for resetting the connecting means to circuit closing position when the circuit breaker is partially removed from the receptacle.

2. A circuit breaker arranged to be inserted in an electrical receptacle including, an insulating block, electrical contacts mounted on said block, means for electrically connecting said contacts to close an electrical circuit through said circuit breaker, means for effecting a disengagement of said connecting means from the contacts when an overload or short circuit occurs in the electrical circuit, and means coacting with the receptacle and controlled by the position of the circuit breaker in the receptacle for resetting the connecting means to circuit closing position.

3. A circuit breaker arranged to be inserted in an electrical receptacle including, an insulating block, electrical contacts mounted on said block, means for electrically connecting said contacts to close an electrical circuit through said circuit breaker, means for effecting a disengagement of said connecting means from the contacts when an overload or short circuit occurs in the electrical circuit, means for resetting the connecting means to circuit closing position, and means mounted in the block and co-acting with the receptacle for preventing the resetting of said connecting means until the electrical connection between the contacts of the block and receptacle is broken.

4. A circuit breaker arranged to be inserted into an electrical outlet receptacle including, an insulating block, electrical contacts mounted on said block, means for electrically connecting said contacts to close an electrical circuit therebetween, a latch carried by said connecting means

for holding said connecting means in circuit closing position and being maintained in place by a fusible material, whereby an overload or short circuit softens said material to permit disengagement of the latch to effect a disengagement of said connecting means from the contacts, and means coacting with the receptacle and for resetting the connecting means and latch to circuit closing position.

5. A circuit breaker arranged to be inserted 10 into an electrical outlet receptacle including, an insulating block, electrical contacts mounted on said block, means for electrically connecting said contacts to close an electrical circuit therebetween, a latch carried by said connecting means 15 for holding said connecting means in circuit closing position and being maintained in place by a fusible material, whereby an overload or short circuit softens said material to permit disengagement of the latch to effect a disengagement 20 of said connecting means from the contacts, and means controlled by the position of the circuit breaker in the receptacle for resetting the connecting means to circuit closing position.

6. A circuit breaker arranged to be inserted 25 into an electrical outlet receptacle including, an insulating block, electrical contacts mounted on said block, means for electrically connecting said contacts to close an electrical circuit therebetween, a latch carried by said connecting means 30 for holding said connecting means in circuit closing position and being maintained in place by a fusible material, whereby an overload or short circuit softens said material to permit disengagement of the latch to effect a disengagement 35 of said connecting means from the contacts, means for resetting the connecting means and latch to circuit closing position, and means mounted in the body and co-acting with the receptacle for preventing the resetting of said connecting means until the electrical connection between the contacts of the body and receptacle is broken.

7. A circuit breaker including, a shell, an insulating block mounted in the shell, said shell and block being arranged to be inserted in an electrical outlet receptacle, electrical contacts mounted on the block having electrical connection with the receptacle when the shell and block are in operative position within said receptacle, means for electrically connecting the contacts to close an electrical circuit therebetween, a latch mounted on said connecting means for holding the latch in circuit closing position and adapted to undergo a limited swinging movement with relation thereto, a fusible material at the point of connection between the latch and connecting means for normally holding the latch in a fixed position thereon, said fusible material being softened when an overload or short circuit occurs to 50 permit swinging of the latch to disengage the same and effect a disengagement of the connecting means with the contacts, and means for resetting the latch and connecting means to circuit closing position.

8. A circuit breaker including, a shell, an insulating block mounted in the shell, said shell and block being arranged to be inserted in an electrical outlet receptacle, electrical contacts mounted on the block having electrical connection with the receptacle when the shell and block are in operative position within said receptacle, means for electrically connecting the contacts to close an electrical circuit therebetween, a latch mounted on said connecting means for holding 70

- the latch in circuit closing position and adapted to undergo a limited swinging movement with relation thereto, a fusible material at the point of connection between the latch and connecting means for normally holding the latch in a fixed position thereon, said fusible material being softened when an overload or short circuit occurs to permit swinging of the latch to disengage the same and effect a disengagement of the connecting means with the contacts, and means controlled by the position of the circuit breaker in the receptacle for resetting the connecting means to circuit closing position.
9. A circuit breaker including, a shell, an insulating block mounted in the shell, said shell and block being arranged to be inserted in an electrical outlet receptacle, electrical contacts mounted on the block having electrical connection with the receptacle when the shell and block are in operative position within said receptacle, means for electrically connecting the contacts to close an electrical circuit therebetween, a latch mounted on said connecting means for holding the latch in circuit closing position and adapted to undergo a limited swinging movement with relation thereto, a fusible material at the point of connection between the latch and connecting means for normally holding the latch in a fixed position thereon, said fusible material being softened when an overload or short circuit occurs to permit swinging of the latch to disengage the same and effect a disengagement of the connecting means with the contacts, means for resetting the latch and connecting means to circuit closing position, and means mounted in the block and co-acting with the receptacle for preventing the resetting of said connecting means until the electrical connection between the contacts of the block and receptacle is broken.
10. A circuit breaker including, a shell, an insulating block mounted in the shell, said shell and block being arranged to be inserted in an electrical outlet receptacle, electrical contacts mounted on the block having electrical connection with the receptacle when the shell and block are in operative position within said receptacle, means for electrically connecting the contacts to close an electrical circuit therebetween, a latch mounted on said connecting means for holding the latch in circuit closing position and adapted to undergo a limited swinging movement with relation thereto, a fusible material at the point of connection between the latch and connecting means for normally holding the latch in a fixed position thereon, said fusible material being softened when an overload or short circuit occurs to permit swinging of the latch to disengage the same and effect a disengagement of the connecting means with the contacts, means for resetting the latch and connecting means to circuit closing position, and means mounted in the block and co-acting with the receptacle for preventing the resetting of said connecting means until the electrical connection between the contacts of the block and receptacle is broken.
11. A circuit breaker including, a shell, an insulating block mounted in the shell, said shell and block being arranged to be inserted in an electrical outlet receptacle, electrical contacts mounted on the block having electrical connection with the receptacle when the shell and block are in operative position within said re-

ceptacle, means for electrically connecting the contacts to close an electrical circuit therebetween, a latch mounted on said connecting means for holding the latch in circuit closing position and adapted to undergo a limited swinging movement with relation thereto, a fusible material at the point of connection between the latch and connecting means for normally holding the latch in a fixed position thereon, said fusible material being softened when an overload or short circuit occurs to permit swinging of the latch to disengage the same and effect a disengagement of the connecting means with the contacts, means for resetting the latch and connecting means to circuit closing position, and a plunger slidable through the block and co-acting with the receptacle for preventing the resetting of the said connecting means until the electrical connection between the contacts of the block and the receptacle is broken, said plunger being spring pressed and adapted to engage the latch and connecting means to reset the same to circuit closing position when the electrical connection between the receptacle and the contacts of the block is broken.

12. A circuit breaker arranged to be inserted into an electrical outlet receptacle including, an insulating block, electrical contacts mounted on said block, a yoke for electrically connecting said contacts to close an electrical circuit therebetween, a latch carried by said yoke for holding said yoke in circuit closing position and being maintained in place by a fusible material, whereby an overload or short circuit softens said material to permit disengagement of the latch to effect a disengagement of said yoke from the contacts, and means for resetting the yoke and latch to circuit closing position.

13. A circuit breaker arranged to be inserted into an electrical outlet receptacle including, an insulating block, electrical contacts mounted on said block, a yoke for electrically connecting said contacts to close an electrical circuit therebetween, a latch carried by said yoke for holding said yoke in circuit closing position and being maintained in place by a fusible material, whereby an overload or short circuit softens said material to permit disengagement of the latch to effect a disengagement of said yoke from the contacts, means for resetting the yoke and latch to circuit closing position, and means mounted in the block and co-acting with the receptacle for preventing the resetting of said yoke until the electrical connection between the contacts of the block and receptacle is broken.

14. A circuit breaker arranged to be inserted into an electrical outlet receptacle including, an insulating block, electrical contacts mounted on said block, a yoke for electrically connecting said contacts to close an electrical circuit therebetween, a latch carried by said yoke for holding said yoke in circuit closing position and being maintained in place by a fusible material, whereby an overload or short circuit softens said material to permit disengagement of the latch to effect a disengagement of said yoke from the contacts, means for resetting the yoke and latch to circuit closing position, and a plunger slidable through the block and co-acting with the receptacle for preventing the resetting of the said yoke until the electrical connection between the contacts of the block and the receptacle is broken.

MARION H. ROWE.
